(57) **CLAIM**

The ornamental design for a floor lamp body, as shown and described.

DESCRIPTION

FIG. 1 is a full front elevational view thereof;
FIG. 2 is an enlarged fragmentary perspective view, for clarity of illustration;
FIG. 3 is an enlarged fragmentary front elevational view of FIG. 2;
FIG. 4 is an enlarged fragmentary right side view of FIG. 2;
FIG. 5 is an enlarged fragmentary left side view of FIG. 2;
FIG. 6 is an enlarged fragmentary back plan view of FIG. 2;
FIG. 7 is a top plan view of FIG. 2; and,
FIG. 8 is a bottom plan view of FIG. 2.

The broken line showing of environmental structure in FIGS. 2, 6, 7 and 8 is for illustrative purposes only and forms no part of the claimed design.
